UNITED STATES PATENT OFFICE.

FREDERICK E. JOHNSTON, OF PITTSBURG, PENNSYLVANIA.

ETCHING-MACHINE.

995,148.

Specification of Letters Patent. Patented June 13, 1911.

Application filed September 26, 1910. Serial No. 583,749.

To all whom it may concern:

Be it known that I, FREDERICK E. JOHNSTON, a citizen of the United States, residing at Pittsburg, in the county of Allegheny and State of Pennsylvania, have invented certain new and useful Improvements in Etching-Machines, of which the following is a specification.

The primary object of this invention is to provide a simple, durable and effective device for rapidly and accurately etching plates, by subjecting them to the action of an erodent or etching solution, and instantly checking the action of the latter upon the plate when the etching operation has been completed.

The invention includes a vertically disposed adjustable plate holder rotatably mounted within a casing, and means for rotating and stopping it as desired, as well as means for spraying the plate separately with an erodent solution and with water, without removing it from the holder or altering the position of the latter.

The invention also includes means for impregnating the erodent solution with air under pressure and projecting it against the face of the plate in an evenly distributed spray, together with an improved form of inclosed etching chamber adapted to hold a supply of erodent solution, and provided with a vent to carry off the fumes generated during the process of etching.

The invention consists of certain novel features of construction, and in the assemblage and combination of parts, hereinafter fully described and claimed, and illustrated in preferred form in the accompanying drawings, wherein:—

Figure 1 is a longitudinal vertical section of an etching machine embodying my improvements. Fig. 2 a sectional plan view taken on line II—II of Fig. 1. Figs. 3 and 4 elevations of opposite ends of the casing. Fig. 5 a face view of one form of mechanism employed to supply air under pressure to the erodent and water sprayers. Fig. 6 a detail view of the adjustable plate holder, and Fig. 7 a detail sectional view of the three-way cock controlling the flow of air to the erodent and water spraying devices.

Referring to the drawings, 2 designates a closed etching chamber or casing adapted to hold a supply of erodent or etching solution, and made from a material capable of resist-

ing the action of the erodent. Casing 2 is preferably provided with a vent 3, drain cock 6, and a tightly fitting removable cover 4, the latter being further provided with a sliding panel 5, formed of glass or any other suitable material to afford a view of the plate during the etching operation and give access to the interior of the casing.

Located within the casing is a vertically disposed rotatable plate holder 7 adapted to accommodate various sizes of plates, and which may be of any preferred construction, such for instance as that illustrated in Figs. 1, 2 and 6 comprising two parallel plate gripping members 8 adjustably connected by a screw 9, and fitted to slide in transversely disposed guide members 10, mounted upon a head 11 provided with a horizontally extended shaft 12. Shaft 12 is fitted to rotate in an externally threaded sleeve or bushing 14, tapped into a boss 13 formed in one wall of the casing to permit of horizontal adjustment of the plate holder within the casing.

The outer end of shaft 12 is provided with a deep socket, angular in cross section and adapted to receive the correspondingly shaped end of a horizontally disposed shaft 15, provided near its opposite end with a slideable clutch 16, moved and controlled by a transversely disposed hand lever 17. Clutch 16 is adapted when in one position on shaft 15 to lock the latter firmly into engagement with the shaft of a suitable motor 18, and when shifted out of such engagement into the opposite position to make frictional contact with a fixed member 19, to bring the moving parts to a standstill. Member 19 may be secured to any conveniently located portion of the mechanism, such for instance as the casing of a blower 20 adapted to be operated by shaft 15 when the latter is in motion, to supply air under pressure to the erodent and water spraying devices, as will be presently described.

While the mechanism just described is well adapted for use in connection with my device I do not limit myself thereto, as any preferred form of rotatable plate holder and air compressing means may be used without departing from my invention. If desired the supply of air under pressure may be obtained from an outside source, in which case member 20 could be dispensed with.

Located within casing 2 in position to spray the face of a plate in holder 7, are one

or more erodent sprayers or atomizers 21, each of which comprises a vertically disposed tube 22 having its lower end immersed in the supply of erodent solution, and a horizontally disposed air nozzle 23, leading through the casing to an air pressure supply pipe 24. The flow of air through the nozzles being regulated to a nicety by valves 25.

One or more water sprayers or atomizers 26, similar in construction to sprayers 21, are mounted in proximity thereto within the casing in position to spray the plate in holder 7, and have their depending tube members leading into a water tank 27, located upon the outside of the casing, and which may be formed integral therewith if desired. Air is supplied to sprayers 26 through a pipe 28, connected to pipe 24 by means of a three-way cock 29, which also connects by means of a pipe 30 with blower 20, as shown, or any other source of air pressure supply. Pipe 30 is provided with a pressure regulating valve 31 which may be of any desired construction.

While any number of erodent and water sprayers may be used in connection with my device I have shown a convenient arrangement and one well adapted to distribute the erodent and water evenly over the plate, which consists of three erodent sprayers 21 arranged horizontally in line with each other and two water sprayers 26 vertically in line above and below the central sprayer 21.

In the operation of my device a supply of erodent or etching fluid is placed in tank 2, as shown by dotted lines at *a* Fig. 1, a properly prepared plate *b* is then fitted in holder 7 and panel 5 closed, the latter being transparent the plate may be observed during the entire etching process. Three-way cock 29 having been turned in position to direct the flow of air through pipe 24 to erodent sprayers 21, clutch 16 is shifted into engagement with the moving shaft of motor 18, whereby plate *b* will be caused to rotate through the medium of shaft 15, and at the same time through the medium of the pressure of air from blower 20 etching fluid will be projected against the face of the plate from sprayers 21. As soon as the plate has been sufficiently etched three-way cock 29 is turned in position to cut off the air from erodent sprayers 21 and direct it through pipe 28 to water sprayers 26, thereby causing a sufficient quantity of water to be projected against the face of the plate, to instantly check the action of what little erodent may remain thereon. When it is desired to check the rotation of shaft 15, lever 17 is shifted to throw clutch 16 out of engagement with the motor shaft and into engagement with friction member 19, thereby bringing all of the moving parts to a standstill. Should three-way cock 29 be turned to close pipe 30, while blower 20 is still in operation, valve 31

will open and permit the air to escape, and will close as soon as the pressure has been sufficiently reduced.

It is characteristic of my device that while the plate is contained in an inclosed casing, it is directly in view and under the control of the operator during the entire etching operation, and may be alternately sprayed with an erodent solution impregnated with air under pressure just previous to its projection against the face of the plate, and with water as desired without being removed from the holder or altering the position of the latter.

It is also characteristic of my device that the distance between the plate and sprayers may be varied to suit different conditions of work and the plate rotated in a vertical plane in range of the sprayers while all objectionable fumes will be carried off from the etching chamber through vent 3.

I claim:

1. An etching machine comprising a casing, erodent sprayers and water sprayers in the casing, a plate holder within the casing and in the range of all of said sprayers, and means for moving the holder without taking the supported plate out of the range of any of said sprayers.

2. An etching machine comprising a casing, erodent sprayers, water sprayers, and a plate holder rotatable within the casing and adapted to support a plate within the range of all of said sprayers.

3. An etching machine comprising a casing, erodent sprayers, water sprayers, air supply means common to the erodent and water sprayers, and a plate holder rotatable within the casing and adapted to support a plate within the range of all of said sprayers.

4. An etching machine comprising a casing, erodent sprayers and water sprayers within the casing, and a plate holder rotatable within the casing on a horizontal axis and adapted to rotate the plate in the range of all of said sprayers.

5. An etching machine comprising a casing, erodent sprayers, water sprayers, and a plate holder rotatable within the casing on a horizontal axis and adapted to rotate a plate while the latter is disposed vertically in the range of all of said sprayers.

6. An etching machine comprising a casing, erodent sprayers, water sprayers, a movable plate holder adapted to movably support a plate in the range of said sprayers, air compressing means connected to the sprayers, and actuating means common to the air compressing means and the plate holder.

7. An etching machine comprising a casing, erodent sprayers and water sprayers within the casing, a plate holder mounted to movably support a plate within the cas-

ing in the range of all of said sprayers, and means for increasing or diminishing the distance separating the holder and sprayers.

8. An etching machine comprising a closed casing provided with a vent and adapted to hold an erodent solution, a horizontally disposed shaft journaled in the casing and provided with plate holding means within the casing, means for rotating the shaft, erodent sprayers within the casing, water sprayers within the casing, air compressing means operated by the shaft, connections between the air compressing means and the sprayers, and valve means controlling the flow of air through the connections and adapted to direct it to the erodent and water sprayers interchangeably.

9. An etching machine comprising a closed casing provided with a vent and adapted to hold an erodent solution, a horizontally disposed shaft journaled in the casing and provided with an adjustable plate holder within the casing, liquid sprayers within the casing, means operated by the shaft for supplying air under pressure to the liquid sprayers, means for rotating the shaft and a clutch movable longitudinally upon the latter and adapted when in one position to connect the shaft to the rotating means and in another position to disconnect them and act as a brake to stop the shaft.

10. In etching machine comprising a closed casing provided with a vent, a horizontally disposed shaft journaled in the casing, a plate holder located within the casing, and adjustably mounted upon the shaft, a clutch slidably mounted upon the shaft and adapted when in one position to act as a brake for the shaft and in another

position connect it to a motor, erodent and water sprayers operating within the casing, means operated by the shaft to supply air under pressure to the sprayers, and means controlling the flow of air and adapted to direct it to the erodent and water spraying devices alternately.

11. An etching machine comprising a closed casing adapted to hold an erodent solution and provided with a vent, a water tank located outside the casing, a spraying device leading from the tank into the casing, an erodent spraying device located within the casing, a plate holder within the casing mounted upon a horizontally disposed rotatable shaft in range of the spraying devices, means for supplying air under pressure to each of the spraying devices alternately, and means for rotating the shaft and operating the air supply means.

12. In combination with an etching machine comprising a plate holder adjustably mounted upon a rotatable horizontal shaft, liquid sprayers and a casing inclosing the plate holder and spraying means, and provided with a vent; of means for supplying air under pressure to the liquid sprayers comprising a blower mounted upon the shaft and operated thereby, a pipe leading from the blower to the sprayers, and a valve mechanism controlling the flow of air under pressure through the pipe.

In testimony whereof, I affix my signature in the presence of two witnesses.

FREDERICK E. JOHNSTON.
